UNITED STATES PATENT OFFICE.

JOHN CYRILLE LARKIN, OF WHITEFIELD, NEW HAMPSHIRE, ASSIGNOR TO
ALSON L. BROWN, WARREN G. BROWN, AND EDWARD RAY, OF SAME
PLACE, AND OSSIAN RAY, OF LANCASTER, NEW HAMPSHIRE.

CAR-BRAKE.

SPECIFICATION forming part of Letters Patent No. 368,838, dated August 23, 1887.

Application filed July 9, 1887. Serial No. 243,808. (No model.)

To all whom it may concern:

Be it known that I, JOHN CYRILLE LARKIN, a citizen of the Dominion of Canada, but now residing at Whitefield, in the county of Coos, 5 of the State of New Hampshire, have invented a new and useful Improvement in Railway-Car Brake Heads and Shoes; and I do hereby declare the same to be described in the following specification and represented in the accompanying drawings, of which—

Figures 1 and 2 are opposite side elevations, and Fig. 3 an inner side view, of a "brake-head" and its "shoe" provided with my invention, the nature of which is defined in the 15 claim hereinafter presented. Fig. 4 is a front elevation, and Fig. 5 an inner side view, of the brake-head, while Fig. 6 is a side view, and Fig. 7 a back view, of the shoe. Fig. 8 is a transverse section of the brake-head, taken 20 through the turn-buckle and its catch-bolt. Fig. 9 is a view of the lower end of the brake-head, showing the T-shaped slot therein.

The brake head and shoe shown in the said drawings are analogous in various respects to those represented in the United States Patent 25 No. 319,731, dated June 9, 1885, and granted on an invention made by myself. There are important differences, however, which go to render the present brake head and shoe simpler in construction and possessing advantages 30 not incident to the other. With the head exhibited in the said patent the shoe could be coupled with it from one side only of the head, whereas according to my present improvement the shoe can be coupled with the head from either of its two opposite sides, which—as railroad employés will understand—is a material advantage, and instead of being held in connection with the head by means of a shoulder and a single-armed turn-buckle, it is secured 35 in place by a double or two-armed turn-buckle, whose longer arm is subsequently secured in position by two studs, one of which is stationary and the other movable and provided with a spring to press it outwardly.

The brake-head A at its lower part has in it a T-shaped slot or opening, b', to receive the circular-headed lug e, extending from the lower part of the shoe B, and, besides, the

brake-head has in its upper part, and going 50 entirely through it, a circularly-curved areal passage, a, which opens out of the hole b for reception of the hanging link C. Projecting downwardly from and at right angles to the curved passage a is another curved passage, d, 55 which goes through the head from side to side, the said two passages being to receive the curved and flanged projection f at the upper part of the shoe. The curves of the passages and projection have their centers in the 60 axis of the lug e. The turn-buckle D, pivoted in the upper part of the head A, has two arms, g and h, each of which extends down from the intermediate part, s, at a right angle thereto, one of such arms being longer than 55 the other, and one being on one and the other on the opposite side of the head A. There projects from one side of the said head a stationary stud, i, and a movable stud, k, they being arranged as shown. The movable stud 70 slides lengthwise in the head, and is held in an advanced position therein by shoulders l m, one of which is formed on the stud and the other in the socket n, for reception of the shank of the stud, there being in the said 75 socket, and between its rear end and that of the stud, a spiral spring, p, for forcing the stud forward. On having introduced the lug e into the opening b' the shoe may be swung from either side of the brake-head into place 80 therein, after which, by turning down the turn-buckle and pressing back the movable stop, and introducing the longer arm of such turn-buckle between the two stops and allowing the movable one to be advanced by its 85 spring, the turn-buckle will so straddle the flanged projection f of the shoe as to hold such shoe in firm connection with the brake-head.

I do not herein claim the brake head and shoe constructed and applied as represented in my said patent; but

I claim—

The brake-head A, provided with the curved passage a d, extending entirely through from 95 side to side, and with the turn-buckle D, having two arms, g and h, as set forth, in combination with the shoe B, having the curved and

flanged projection *f*, formed to fit it and pass into such passage from either side of the brake-head, the said brake-head having the stationary stud *i*, the movable stud *k*, and the operative spring *p* of the latter for holding the turn-buckle in its depressed position, and such head and shoe having the headed lug *e*

and the T-shaped groove or slot for reception of such lug, as specified.

JOHN CYRILLE LARKIN.
